GOLFER'S GLOVE

Sidney T. Tudor, Sacramento, Calif.

Application April 11, 1957, Serial No. 45,690

Term of patent 14 years

(Cl. D3—11)

Fig. 1.

Fig. 2.

Fig. 3.

Fig. 4.

I claim:

The ornamental design for a golfer's glove, as shown.
